(57) **CLAIM**

I claim the ornamental design for the cup with lid, as shown
and described.

DESCRIPTION

FIG. 1 is a perspective view of a cup with lid showing my
new design;

FIG. 2 is a front elevational view thereof, the opposite side
being a mirror image thereof;

FIG. 3 is a left side elevational view thereof, the opposite side
being a mirror image thereof;

FIG. 4 is a top plan view thereof;

FIG. 5 is a bottom plan view thereof;

FIG. 6 is a cross-sectional view thereof taken along line
6—6 of FIG. 4; and,

FIG. 7 is a cross-sectional view thereof taken along line
7—7 of FIG. 2.
